UNITED STATES PATENT OFFICE.

GEORGE S. WITHAM, JR., OF HUDSON FALLS, NEW YORK.

SLICE FOR PAPER-MAKING MACHINES.

Application filed October 5, 1921. Serial No. 505,538.

To all whom it may concern:

Be it known that I, GEORGE S. WITHAM, Jr., a citizen of the United States, residing at Hudson Falls, in the county of Washington and State of New York, have invented certain new and useful Improvements in Slices for Paper-Making Machines, of which the following is a specification.

The object of this invention is to provide an improved form of slice for paper making machines, which is so constructed and may be so operated as to afford a more perfect adjustment of the machine for different kinds of stock and for varying amounts of stock, thereby increasing the efficiency of the machine as a whole.

In many paper machines of the Fourdrinier type, what is known as a "slice" is employed, consisting mainly of a sheet of metal extending vertically over the surface of the Fourdrinier wire and provided with devices for adjusting it vertically in such manner as to regulate the distribution of the stuff on the wire.

In none of these machines previously used, however, have devices been employed for readily giving the required adjustment, and as a consequence, variations in the slowness or the freeness of the stock as it flows on the wire causes paper to be produced that lacks uniformity. It has been customary to introduce more or less water in the machine or to change the position of the slice, which requires of the operator both time and labor to make adjustments on the front and back side of the machine. These adjustments in water flow, if not carefully made, cause liberation of lumps and foam from the head box and at various other points resulting in breaks or imperfections in the sheet. Moreover, it is essential that the speed at which the stuff is delivered to the wire should be as near as possible to the speed of the wire. In order to accomplish these results, mechanism of special design is required. By my improvements I have made it possible to introduce more water in the system to offset any variations in the slowness or freeness of the stock, thus giving a good drainage area to the stock under static pressure before going under the slice. I am also enabled to furnish the same amount of stock to the wire at a far greater

rate of speed. Other features of the invention will be hereinafter specified.

55

In the accompanying drawings:

Figure 1 is a view partly in side elevation and partly in section of a portion of a Fourdrinier paper making machine with my improvements applied.

60

Figure 1^a is a detail view of portions of the slice mechanism, most of the parts being shown in section.

65

Figure 2 is a plan view of the slice mechanism and parts associated therewith.

Figure 3 is a perspective view of the slice proper with parts at the center broken away and with the side wings removed.

65

Figure 3^a is a section on the line 3—3 of Figure 3.

70

Figure 4 is a view partly in section and partly in elevation of the slice mechanism.

Figure 5 is a perspective view of portions of the slice mechanism with parts separated in order to illustrate the construction of these parts.

75

Figure 6 is a rear elevation of portions of the slice mechanism.

The head box A is of the usual kind. It is provided with the usual apron B and the Fourdrinier wire C extends around a breast roll D supported beneath the apron in any suitable way. The deckle straps E extend around rollers F and operate in the usual way. A bracket F' clamped to a vertical post G supports a standard H which carries the slice mechanism L. The bracket F' may be adjusted vertically on the post G, and said post G may be supported in any suitable way. The drawings, Figure 1, show the slice proper in three different positions, namely, in a truly vertical position and in inclined positions in front and rear of the vertical.

80

Figures 2, 3 and 4 show more clearly the construction of the slice. As shown, it consists of a central portion N provided with ribs n by which it is braced and strengthened and may thus resist strain. The central portion is provided at each end with an adjustable wing O or P (Fig. 2). Each of these wings overlies the central part N and each wing carries set screws Q extending through slots q in the slice. By these devices the slice may be widened or narrowed to the desired extent to accommodate deckle

straps arranged varying distances apart. The slice N is supported by rods R which extend into sockets r in the slice and these rods R are supported by devices next to be described, by means of which the slice may be given desired adjustments.

Each rod R extends into a sleeve s attached to the rod at s' and each sleeve s carries a collar t having a laterally projecting finger t'. The sleeve s extends through a clamping member T, split at t² and carrying a bolt t³ supplied with clamping nuts t⁴, t⁵. By these devices the sleeve s and the rod are securely clamped to the clamping member T and the turning of the rod and sleeve will be prevented after the sleeve and rod are adjusted and the nuts are screwed home.

The clamping member T is also split at u and carries a screw U, by means of which the clamping member may be set and secured on the sleeve U' (Fig. 1^a) which rests on the flange u' formed on the screw U², which has a lower end u³ extending through the top of the standard H. By these devices, the clamping member may be set at any desired elevation on the sleeve U' and as the screw U² has a threaded connection with the sleeve U', by turning the screw delicate adjustments may be given to the parts and thus to the slice.

The fingers t' carried by the rods R and the sleeves s extend between lugs w, w' on the member T, and these lugs carry adjusting screws W, W', by means of which the rods R and sleeves s may be turned in such manner as to hold the slice in either a vertical or in an inclined position.

The mechanism shown may be readily applied to various kinds of paper making machines. The parts are made strong enough to resist all strain, delicate adjustments may be given to the slice, and when the adjustments are once made, the parts are held firmly against all strains. It will be observed that the slice proper is so mounted that it is turned about a horizontal axis, and it may also be raised bodily vertically. When the desired vertical adjustment is given, more delicate adjustments may be given by moving the slice about its horizontal axis. This varies the position at the lower edge of the slice above the wire and it also varies the distance between the slice and the edge of the apron so as to expose a greater area of the wire within the head box. It will be observed that by my improvements I have made it possible to introduce more water into the system to offset any variations in the slowness or freeness of the stock, thus giving a greater drainage area to the stock under static pressure before the stock goes under the slice. Moreover, by changing the position of the lower edge of the slice longitudinally of the

machine I am enabled to furnish the same amount of stock to the wire at a far greater rate of speed. By my improvements the nature of the stock can be changed and still maintain the proper depth of stock in the pond or head box. Thus when the slice is placed at the forward end of the apron and stands at a previously adjusted distance from the Fourdrinier wire, the stock will flow under a definite weight depending on the consistency of the stock and the size of the opening under the slice, and if at any time the stock may become too wet, this condition may be offset by giving the slice a pivotal movement, thereby pushing the lower edge of the slice to a point further away from the forward end of the apron. This forward movement will increase the screening area, all of which is under static pressure due to the height of the stock in the pond. By the devices shown, the lower edge of the slice may be moved forward, thus enabling the operator to change the nature of the stock and yet maintain the proper height in the pond. The slice may be adjusted vertically without giving it a pivotal movement, or it may be adjusted about a horizontal axis without any separate vertical adjustment. A change can readily be made from light weights to extremely heavy weights of stock without shutting down the machine. It is only necessary to adjust certain hand nuts or set screws to give all the necessary adjustments for varying the conditions. It is well understood that when operating on free or heavy stock much more water must be handled and much more water must be drained from the surface of the wire. My improved slice makes it possible to increase the distance of the slice from the apron and to drain the water out of the sheet at the required speed.

It will be understood that the brackets F' may be so applied to the posts G that they may hold the slice mechanism at substantially the required height. In order to vary this vertical position, the screws U² may be employed. These screws U² give vertical adjustment to the sleeves U' to which the clamping members T are applied. Furthermore, these clamping members can be given desired vertical adjustments on the sleeves by tightening and loosening the screws U, but during the operation of the machine, the desired vertical adjustments may be given by means of the screws U². The pivotal or swinging adjustments of the slice are given by the screws W, W'. When it is necessary to make such arrangements, the nuts t⁴, t⁵ on the screws t³ are loosened, thus making it possible to turn the rods R, sleeves s and the slice about a horizontal axis, and such turning of all these parts is made by means

of the screws W , W' which engage the fingers t' . After such adjustments have been made, the nuts t^4 , t^5 are tightened so that the slice will remain firmly held in the position to which it is set.

I claim as my invention:

1. A slice for paper making machines, provided with means for adjusting it vertically and with devices for adjusting it 10 pivotally about a horizontal axis.

2. A slice for paper making machines, mounted to move about a horizontal axis and provided with devices for adjusting it about said horizontal axis and for holding 15 it in its adjusted position.

3. A slice for paper making machines, provided with means for supporting it in proximity to the head box and for clamping it in position in combination with means 20 for adjusting it vertically and with other means for moving it about a horizontal axis and for holding it rigidly in its adjusted position.

4. A slice for paper making machines, comprising a body portion mounted to 25 move about a horizontal axis, and provided with adjustable wings at opposite ends carrying devices for holding the wings in adjusted positions.

5. A slice for paper making machines, 30 comprising a central body portion provided with adjustable wings, means for supporting the slice, devices for adjusting the slice vertically, and means for turning the slice about a horizontal axis and for holding it 35 in adjusted positions.

6. In a paper making machine, the combination with a head box, of a slice, clamping members to which the slice is connected, a standard on which the clamping members 40 are vertically adjustable, and means carried by the clamping members for adjusting the slice about a horizontal axis.

In testimony whereof, I have hereunto subscribed my name.

GEORGE S. WITHAM, JR.
